LATCH HANDLE

John P. Tarbox, Philadelphia, Pa., assignor to
 Edward G. Budd Manufacturing Company,
 Philadelphia, Pa., a corporation of Pennsylvania.

Application June 27, 1932, Serial No. 619,377

2 Claims. (Cl. 292—347)

This invention relates to vehicles and more particularly to a full vision latch operating mechanism for the doors. It has for its principal object, the embodiment in a latch mechanism, having preferably a straight actuating spindle positioned between the jamb face of the door and the edge of a reciprocable member of substantially full door width, of an actuating mechanism externally of the door walls of substantially Y-shape having one arm of the Y secured to the latch operating spindle and the other arm comprising the main body of the handle integral with the web at a point nearer to its inner end than to its outer end and having its web axis off-set from the axis of the through spindle, to a degree insuring non-interference between adjacent handles.

This invention will be more fully understood and its advantages more certainly appreciated from a comprehensive reading of the description following in connection with the accompanying drawing.

In the construction of vehicle doors wherein the maximum amount of visual opening is attained, complications arise as to the door operating mechanism. Door latches for vehicles inherently must be operable from both the inside and outside. If the window is substantially of the full door width, some means of interconnecting the mechanism on either side of the pane of glass must be constructed.

This situation, generally involves either, the jamb face of the door having a protuberance thereupon and internally of said protuberance an interlinking mechanism connecting the latch and its operating arms at either side of the window, or having a straight spindle passing, between the edge of the pane of glass and the door jamb face, and either displacing the operating handles vertically or having them so close to the edge of the door, that serious inconvenience results or that the door appearance be seriously marred in which latter instance, the door handle is moved closer to the door edge than is desirable for harmonious contouring of the car body.

I have accomplished the above desirable features, while at the same time avoiding the above enumerated disadvantages, by constructing my latch operating mechanism preferably so that the door jamb face is not marred, a through spindle can be used and characterized by the outside positioning of the operating handle, visually substantially the same as under conditions wherein the door window is appreciably of less width than the door itself.

In the drawing, Figure 1 is a partial elevation

of a vehicle body showing the door structure embodying the present invention.

Fig. 2 is a partial plan in cross section through the vehicle center post showing the co-operative relation of the parts.

Fig. 3 is an enlarged section adjacent the latch operating mechanism centrally of Fig. 1.

According to this invention I preferably interpose the interconnecting spindle, between the latch mechanism and the outside operating handle, juxtaposed between the jamb face of the door and the glass run channel. The vehicle body constitutes the customary sheet metal parts having front and rear doors 10 and 11 arranged to abut on either side of the B-post 12. The B-post is constituted of sheet metal parts having a keeper 13 in each of its opposite faces. The doors 10 and 11 are similar in material and composition with the exception that their peripheral contour is different, corresponding to the complementary sections of the vehicle body.

The door 10 has inner and outer walls 14 and 15 of sheet metal, the outer of which is reversely bent at 16 receiving a corresponding flange portion 17 of the inner wall, the two being in locked relation and constituting the outer overlap of the door upon the crevice of the jamb. Secured to the inner panel 14 by suitable fastening means is a latch housing 18 having interiorly thereof the necessary lock parts. The window glass 19 is arranged for vertical reciprocation within the door in suitable glass run channels 20 and 21 secured to the inside jamb faces 23 of the doors respectively and another such channel secured at the hinge rail of each door in a corresponding manner. The latter mounting, not being a part of the present invention, is not shown, it being sufficient that the said mountings are substantially the full width of the door with the side edges 22 of the glass a very short distance from the jamb face 23 of the door.

The slide channels shown are made up from two pressed metal members 24 and 25 having complementary portions 26 with a slot 27 adapted to receive the through spindle 28 interlinking the handle 29 and the latch housing 18. By means of the clockwise or counterclockwise motion of the handle 29 about the axis of the spindle A—A the end 30 of the latch bolt is withdrawn from engagement with the keeper 13 thereby allowing the door to be opened from the outside. The door may be opened from the inside by a suitable handle 36 secured to a spindle 37 which passes through the door wall 14, the escutcheons or bearing member 38 to the latch housing 18. The

spindle 28 passes through the outer door wall 15 and has an escutcheon or bearing member 39.

Interposed within the channel and between the metal channel member and the window pane is a 5 suitable shock absorbing material 31. The handle 29 is of substantially Y-section having one arm 32 simulating the usual escutcheon plate and thereby eliminating that member and hiding the bearing member 39. This arm is secured near 10 its outer edge 33 to the spindle 28 and at the opposite end becomes integral with the web portion 34. The web portion 34 is offset from the axis A—A of the through spindle upon the axis B—B. The other arm 35 of the Y-section constitutes the main body of the Y and is removed 15 from the axis A—A of the spindle to a degree insuring non-interference between adjoining handles while at the same time not interfering with the efficient operation of the latch mechanism nor 20 marring the beauty and general outside appearance of the car. This would result with the handles placed immediately opposite the through spindle axis. This outer arm, constituting essentially the handle of the door, is integral with the 25 web portion of the Y nearer its inner end than its outer end.

It will be observed that resulting from the construction shown no projections extend beyond the jamb face of the door, other than the lock 30 bolt end 30, by means of which the door is secured in closed relation to the keeper. This direct construction between the lock or latch mechanism and the handle gives a strong simplified mechanism with the elimination of parts formerly

considered necessary. It is neat and constitutes many desirable features of formerly numerous parts into a lesser number of simplified members as previously described.

Although a straight spindle is not essential to my invention I find it to be the most simplified construction and it is most admirably suited to my improvements. Many modifications can be apparent and I aim to cover these in the claims appended hereto and made a part hereof.

What I claim is:

1. Latch mechanism for vehicle doors including an oscillatable latch operating spindle extending across the door at its free vertical edge and means for oscillating said spindle, characterized by said means comprising a handle having a portion connected to the outer end of the spindle and extending inwardly of the free vertical edge of a door a substantial distance along the outer face of the door, and a portion connected to the 15 inner end of said inwardly extending portion and extending laterally outwardly of the plane of the door, and a portion connected to said outwardly extending portion and extending substantially parallel to the outer face of the door in spaced 20 relation thereto and arranged to be grasped by the hand of an operator.

2. The combination according to claim 1 in which the last-named portion of the handle of said last-named means is characterized by a portion projecting over the first-named portion and substantially concealing it from the outside.

JOHN P. TARBOX.
